UNITED STATES PATENT OFFICE.

BENJAMIN D. MINER, OF INDIANAPOLIS, INDIANA.

DESIGN FOR A CHAIR.

SPECIFICATION forming part of Design No. 32,969, dated July 17, 1900.

Application filed June 2, 1900. Serial No. 18,907. Term of patent 7 years.

To all whom it may concern:

Be it known that I, BENJAMIN D. MINER, a citizen of the United States, residing at Indianapolis, in the county of Marion and State of Indiana, have invented and produced a certain new Design for a Chair, of which the following is a specification.

As shown in the drawing, the leading or material feature of my design consists of a base having two sides, each the shape of the letter A, with ornamental bars reaching from one of said sides to the other, a body-frame located above the base having cut-away or open sides forming front and rear standards which slope or lean in a backward direction, said standards being connected by horizontal cross-bars forming arms, said side frames having underscalloped edges, a square-sided upholstered box-seat, a leg and foot support extending down from the seat in front, wider at top than at bottom, and a back having a middle receding or backward curve.

1 1 are the A-shaped sides of the base, the outer members of which are curved inwardly from top to bottom.

2 are straight cross-bars extending from side to side of the base and having the scroll-braces 3.

4 is the body-frame, cut away at the sides to form the rearwardly-leaning standards 5 and 6. The ends of the frame have the semi-circular parts a, leading in from which are

the scallops b, of long curvature or radius, and between and connecting them are the two scallops b' b', of much shorter curvature.

35

7 is a horizontal bar connecting the tops of the standards 5 and 6. There is one of these bars on each side of the chair upholstered and rounded on top.

8 is the leg and foot support. It has an upholstered front of gradually-lessening thickness from top c to bottom d, and the bottom foot-rest 9 is reduced in width centrally to form the end enlargements e e.

10 is the frame of the back, which is curved to the rear in its middle portion and terminates at top with scroll 11 in relief.

12 is the upholstered portion of the back, which extends forward of the frame and is curved and rounded to conform to the shape 50 of the frame.

Having described my invention, what I claim as new, and desire to secure by Letters Patent, is—

The design for a chair, as herein shown and described.

In witness whereof I have hereunto set my hand and seal, at Indianapolis, Indiana, this 22d day of May, A. D. 1900.

BENJAMIN D. MINER. [L. S.]
